UNITED STATES PATENT OFFICE.

LOTHAR W. FABER, OF PORT RICHMOND, NEW YORK.

DESIGN FOR AN ERASER.

SPECIFICATION forming part of Design No. 23,411, dated July 3, 1894.

Application filed May 29, 1894. Serial No. 512,934. Term of patent 14 years.

To all whom it may concern:

Be it known that I, LOTHAR W. FABER, a citizen of the United States, residing at Port Richmond, in the county of Richmond and 5 State of New York, have invented a new Design for an Eraser, of which the following is a full, clear, and exact specification.

The leading feature of this design for an eraser consists in the triangular configuration o with rounded corners and raised ornamental side plates.

In the drawings:—Figure 1. is a side view, and Fig. 2. is a section at the line $x x$.

The ornamental shape and configuration of

the eraser is triangular with rounded corners 15 at a . and raised triangular side plates with edges b . substantially parallel to the outer edges of the eraser. The circular center c . does not form a necessary part of this design.

I claim—

The design for an eraser substantially as shown and described.

Signed by me this 26th day of May, 1894.

LOTHAR W. FABER.
